UNITED STATES PATENT OFFICE

GEORGE W. RAPPOLD, OF MASPETH, NEW YORK

PENCIL SHARPENER

Application filed June 12, 1930. Serial No. 460,585.

This invention relates to new and useful improvements in a pencil sharpener.

The invention has for an object the provision of a device of the class mentioned which is of simple durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a device constructed according to this invention.

Fig. 2 is a vertical sectional view taken on the line 2—2 of Fig. 1.

Fig. 3 is a transverse vertical sectional view taken on the line 3—3 of Fig. 1.

Fig. 4 is a horizontal sectional view taken on the line 4—4 of Fig. 2.

Fig. 5 is a side elevational view of the device seen from the left hand side of Fig. 3.

Fig. 6 is a fragmentary enlarged detailed sectional view of a portion of Fig. 3.

Fig. 7 is a bottom view of Fig. 6.

Fig. 8 is a fragmentary sectional view taken on the line 8—8 of Fig. 6.

Fig. 9 is a perspective view of one of the blade holders per se.

Fig. 10 is an enlarged fragmentary sectional view taken on the line 10—10 of Fig. 9.

Fig. 11 is an enlarged fragmentary sectional view taken on the line 11—11 of Fig. 2.

Fig. 12 is a perspective view of a knife carriage used in the device.

The pencil sharpener comprises a casing 10 having openings 11 and opposite vertical sides 12; a knife carriage 13 vertically slidably mounted in the casing 10, a vertical knife guide 14 mounted in the casing 10,

means for manually adjusting said guide, a pencil guide or holder 15 rotatively mounted in the casing, means for slightly turning said pencil guide upon each cycle of cutting knives for sharpening a pencil inserted in the guide, 50 knife holders 16 pivotally mounted in said knife carriage 13 and having handle portions 17 projecting through said openings 11 in the casing for depression to pivot knives in the holders against and down along said guide 55 14, and means for automatically raising said knife carriage 13 after each depression.

The casing 10 is shown of two sections, namely a large base section 18 attached to an upper section 19. A door 20 is pivotally 60 arranged in the lower section and a coaxial spring 21 is arranged upon the pivot point of the door for normally urging it closed. The door is shown having a handle 22 for its manual opening. Dot and dash lines 23 in Fig. 3 65 indicate a partially opened position of the door. Shavings within the casing can be removed from this door.

A knife carriage 13 is made from sheet metal and has a plurality of vertical sides 24 70 and 25 and a top side 26. The vertical corners of the sides 24 and 25 are cut out as indicated by reference numeral 27. Bottom lugs 28 are formed upon the sides 25 and extend beneath the cut out 27. Springs 29 75 are attached at one of their ends upon the lugs 28 and at their other ends to the top of the casing 10. These springs constitute the means for automatically raising said knife carriage 13 after each depression. A pair of 80 opposite horizontal top edges of the knife carriage 13 are cut out as indicated by reference numeral 30. These cutouts allow the passage of the knife holders 16 so that the handle portions extend therefrom, while the other portions are disposed within the carriage. A 85 slidable mounting of the knife carriage is accomplished by the sides 24 and 25 being in slidable relation with the inner sides of the top section 19 of the casing.

The vertical knife guide 14 comprises a pair of vertical rods 31 spaced from each other and arranged upon opposite sides of the holder 15. The top ends of these rods extend from the top of the casing 10. The top portions of the rods 31 are circular in horizontal cross section as may be seen from an inspection of Fig. 11, while the lower portions are tapered and of elliptical shape indicated by the dotted lines in this figure. The lowered pointed ends of the rods 31 rest upon a block 32 attached within the casing 10. This block extends transversely across the bottom section 18 of the casing so as to be located directly beneath the pencil holder 15. A pencil inserted through the holder rests upon this block as clearly illustrated in Fig. 2. The means for manually adjusting the knife guide 14 comprises radial arms 33 attached upon the top extended ends of each of the rods 31 and connected to each other by a connecting rod 34. The points of connection between the rod 34 and the arms 33 are pivotal so that the rod may be moved for simultaneously turning both of the arms

The pencil guide 15 comprises a tube 35 rotatively mounted in a collar 36. This collar is threadedly engaged in the top of the casing 10 and has a top edge at right angles to the main portion of the collar. The top of the tube 35 is bent outwards so that it has a portion 37 resting against the top edge of the collar 36. A washer 38 is disposed immediately below the top of the casing 10 and upon the tube 35 and a ring 39 is positioned below the washer and attached upon the tube by a rivet 40. The lower end of the tube 35 is provided with a plurality of curved fingers 41. Intermediate its ends the tube 35 is formed with a plurality of curved impressed portions 42 for acting against an inserted pencil and holding the pencil against relative rotations to the tube.

The means for slightly turning said pencil guide upon each cycle of the cutting knives comprises a plurality of teeth 43 projecting from the bottom of the ring 39 and engageable by a pair of fingers 44 cut out from the top portion 26 of the knife carriage 13. The fingers 44 have opposed free ends extended upwards above the top 26 and resilient so that as the carriage 13 moves to the raised position, these free ends engage a pair of the teeth 43 and rotate the tube 35 as the carriage 13 completes its upstroke. A finger 45 is rigidly attached upon the inner side of the top portion of the casing 10 and has a flat portion acting against the edge of the ring 39 for normally frictionally holding the tube 35 against free rotation.

Each knife holder 16 has a substantially vertical portion 46 integral with the horizontal handle portion 17. The top surface of the handle portion is nurled as indicated on the drawings. The junction between the

portions 17 and 46 is curved and turned around upon a pin 47. This pin has its free ends attached through the slots 27 of the knife carriage 13. Springs 48 are attached upon the pin 47 and act against the portion 46 for normally resiliently preventing free turning of the pin 47 outside of certain limits. The portion 46 of the knife holder is formed with a plurality of bent fingers 49 along the bottom edge and other bent fingers 50 on the sides for engaging a razor blade and holding the blade in place. Between the bottom fingers 49 there are spaces 51 so that a portion of the blade is exposed and may act against the guides 14 and against a pencil inserted in the pencil holder. The lower part of the portion 46 is slightly offset from the other portion as indicated by reference numeral 52 providing an offset edge for receiving the top edge of an inserted blade. On the drawings the blades are indicated by reference numerals 53. They are shown inserted within the knife holders. The pencil on the drawings is indicated by reference numeral 54.

The operation of the device may be traced by assuming the parts in the position as illustrated in Fig. 3. The blade holders 16 may be manually moved downwards by pressing downwards upon the handle portion 17. Downward pressure upon the handle portions causes the knife holders to tend to pivot around the pins 47 and this urges the blades 53 against the knife guides 14. Downward pressure upon the handle portion 17 moves the knife carriage 13 downwards and the blades 53 cut off opposite portions of the pencil 54 as directed by the tapered portions of the rods 31 of the knife guides. After complete depression the handles 17 are released so that the springs 29 may return the knife carriage to its raised position.

As the knife carriage reaches its raised position the fingers 44 act against the teeth 43 of the ring 39 so as to slightly rotate the tube 35 and consequently turn the pencil 54 to a new position. Then the connecting rod 34 is slightly moved so as to move the knife guide 14 to a new position. The new position referred to is a slight rotation of the rods 31 so that the major axis of the elliptical tapered portions of the rods move and allow another cut upon the pencil 54. Then the handle portions 17 are again depressed for taking the second cut. The operation is repeated until the pencil has been completely pointed.

It is to be understood that the guides 14 may also be set to correspond with a definite cutting shape of the pencil and left in the set position throughout the operation of sharpening.

While I have shown and described the preferred embodiment of my invention, it is to be understood that I do not limit myself to the precise construction herein disclosed and

the right is reserved to all changes and modifications coming within the scope of the invention as defined in the appended claims.

Having thus described my invention, what I claim as new, and desire to secure by United States Letters Patent is:—

1. A pencil sharpener, comprising a casing having openings on opposite vertical sides, a knife carriage vertically slidably mounted in said casing, a vertical knife guide mounted in said casing, means for manually adjusting said guide, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression.

2. A pencil sharpener, comprising a casing having openings on opposite vertical sides, a knife carriage vertically slidably mounted in said casing, a vertical knife guide mounted in said casing, means for manually adjusting said guide, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said knife carriage being of box-like construction having vertical sides and a top.

3. A pencil sharpener, comprising a casing having openings on opposite vertical sides, a knife carriage vertically slidably mounted in said casing, a vertical knife guide mounted in said casing, means for manually adjusting said guide, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said knife carriage being of box-like construction having vertical sides and a top, the vertical corners of said sides being cut out and lugs being arranged on the sides for connection with one of the ends of a plurality of springs attached at their other ends to the top of the casing and constituting said means for automatically raising said knife carriage after each depression.

4. A pencil sharpener, comprising a casing having openings on opposite vertical sides, a knife carriage vertically slidably mounted in said casing, a vertical knife guide mounted in said casing, means for manually adjusting said guide, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said knife carriage being of box-like construction having vertical sides and a top, opposite top corners of said vertical sides and the horizontal top being cut out for the passage of said knife holders so that the handle portions may extend through said openings and other portions be disposed within said carriage. 70 75 80 85

5. A pencil sharpener, comprising a casing having openings on opposite vertical sides, a knife carriage vertically slidably mounted in said casing, a vertical knife guide mounted in said casing, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said knife carriage consisting of a box-like construction having vertical sides and said sides being in slidable contact with the interior of the casing constituting the slidable mounting. 100 105 110

6. A pencil sharpener, comprising a casing having openings on opposite vertical sides, a knife carriage vertically slidably mounted in said casing, a vertical knife guide mounted in said casing, means for manually adjusting said guide, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said vertical knife guide comprising vertical rods arranged on opposite sides of the pencil holder and extended through the top of the casing and having tapered lower ends of approximately elliptical shape and

resting at the bottom upon a block attached within said casing.

7. A pencil sharpener, comprising a casing having openings on opposite vertical sides, a knife carriage vertically slidably mounted in said casing, a vertical knife guide mounted in said casing, means for manually adjusting said guide, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said vertical knife guide comprising vertical rods arranged on opposite sides of the pencil guide and extended through the top of the casing and having tapered lower ends of approximately elliptical shaped and resting at the bottom upon a block attached within said casing, said means for manually adjusting the knife guide comprising radial arms attached to the extended ends of said rods, and a connecting rod between said radial arms.
8. A pencil sharpener, comprising a casing having openings on opposite vertical sides, a knife carriage vertically slidably mounted in said casing, a vertical knife guide mounted in said casing, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, said pencil guide comprising a tube having its top end turned flat and rotatively supported in a collar attached within the top of the casing, a ring being attached upon said tube within said casing, and a washer being disposed between said ring and the inside of the casing.
9. A pencil sharpener, comprising a casing having openings on opposite vertical sides, a knife carriage vertically slidably mounted in said casing, a vertical knife guide mounted in said casing, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically

raising said knife carriage after each depression, each of said knife holders having a substantially vertical portion integral with said handle portion and extended around a pin fixed within said knife carriage, and fingers from said substantially vertical portions for engaging and holding blades in place. 70

10. A pencil sharpener, comprising a casing having openings on opposite vertical sides, a knife carriage vertically slidably mounted in said casing, a vertical knife guide mounted in said casing, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, each of said knife holders having a substantially vertical portion integral with said handle portion and extended around a pin fixed within said knife carriage, fingers from said substantially vertical portions for engaging and holding blades in place, and said substantially vertical portions formed with spaces between the bottom fingers for exposing the blades so that they may act against a pencil inserted in the pencil guide. 80

11. A pencil sharpener, comprising a casing having openings on opposite vertical sides, a knife carriage vertically slidably mounted in said casing, a vertical knife guide mounted in said casing, a pencil guide rotatively mounted in said casing, means for slightly turning said pencil guide upon each cycle of cutting knives for sharpening a pencil inserted in said guide, knife holders pivotally mounted in said knife carriage and having handle portions projecting through said openings in the casing for depression to pivot knives in the holders against and down along said knife guide, and means for automatically raising said knife carriage after each depression, each of said knife holders having a substantially vertical portion integral with said handle portion and extended around a pin fixed within said knife carriage, fingers from said substantially vertical portions for engaging and holding blades in place, and a leaf spring attached on the said pin for normally resiliently holding said pin from turing outside of certain limits. 100

12. A pencil sharpener, comprising a casing having openings on opposite vertical sides, a plurality of longitudinally stationary vertical knife guides mounted in said casing, a pencil guide rotatively mounted in said casing, cutting knives for sharpening a pencil inserted in the pencil guide, means for supporting said cutting knives comprising a knife carriage vertically slidably mounted in 120

said casing and knife holders pivotally mounted in said knife carriage and having handle portions projecting through said openings in the casing for depression to pivot the 5 knives in the holders against and down along said longitudinally stationary vertical knife guides, means for automatically raising said knife carriage after each depression, and means for slightly turning said pencil guide 10 upon each cycle of the cutting knives.

In testimony whereof I have affixed my signature.

GEORGE W. RAPPOLD.
